FOOT SUPPORTING MEANS

Filed Jan. 17, 1929

Inventor:
William M. Scholl.

By: *Charles Scholl* Att.

UNITED STATES PATENT OFFICE

WILLIAM M. SCHOLL, OF CHICAGO, ILLINOIS

FOOT SUPPORTING MEANS

Application filed January 17, 1929. Serial No. 333,039.

This invention relates to improvements in foot supporting means, and more particularly to foot supporting means of the character of arch supports, insoles, and devices of similar nature, although many and varied uses may be made of the invention hereinafter described without departing from the spirit of the invention, as will be apparent to one skilled in the art.

10 In the past, many and varied devices of the character of arch supports, insoles, and the like, have been developed, but in most instances have proven objectionable in that moisture emanated from or produced by the 15 foot of a user, or of moisture seeping through the footwear of a user from an outside source, tended to materially deteriorate these formerly known devices by causing the metal parts thereof, if any, to rust, or by causing the other 20 portions of these formerly known devices, such as leather, felt, etc. portions, to rot or become soaked to such an extent that they would have to be removed from the footwear of a user and dried. In these formerly 25 known devices, especially if the base means thereof were made of felt or the like, perspiration from the foot of a user rendered them in a short time undesirable for further use.

The present invention has been designed to 30 overcome the above noted defects and objections in the provision of a device of a character described herein in which the base means thereof are fully and completely protected from moisture emanating from or 35 caused by the foot of a user.

The invention also seeks the provision of a 40 foot supporting device capable of preventing moisture seeping through the lower portion of the footwear of a user from contacting with the foot of the said user.

A further object of the present invention is the provision of an arch support, insole, or the like, having moisture-proof means disposed between the base means and upper covering of the device.

While some of the more salient features, 50 characteristics, and advantages of a device embodying this invention have been above pointed out, others will become apparent from the following disclosures.

The invention includes these and other features of construction and combination of parts hereinafter described, and shown in a preferred form in the drawing, as more particularly indicated by the claims.

On the drawing:

Figure 1 is a bottom plan view of a device embodying features of the present invention.

Figure 2 is substantially a central vertical sectional view of the device shown in Figure 1 still in inverted position.

Figure 3 is a view similar to Figure 2 showing a slight modification of the device.

Figure 4 is a transverse vertical sectional view taken substantially as indicated by the lines IV—IV of Figure 2, but with the device in upright position.

As shown on the drawing:

In the structure selected to illustrate an embodiment of the present invention, there is shown an arch support including a base member 5 which in this instance is shown in the form of a metallic plate shaped so as to effectively support the longitudinal arch and plantar region of a foot, but it is to be clearly understood that the base member 5 may be composed of metal, felt, cork, or any desirable material of any desirable configuration.

To provide a more desirable and comfortable rest for the foot of a user, a flexible covering 6, which may be of leather or any suitable material, is provided to overlie the base member 5.

Disposed between the covering 6 and the base member 5 is a sheet of water or moisture-proof material 7, such, for example, as rubberized sheeting, which as more clearly shown in Figures 1 and 2, may be cut to a size just sufficient to overlie the base member 5, leaving the remaining portion of the covering 6 contact directly with the footwear of a user. As seen more clearly in Figure 4, the moisture-proof material 7 is preferably secured in any desirable manner, for instance by a suitable adhesive, to the top covering 6 so that the same will always flex with the covering and not tend to become loosened or to curl around the base member or in some similar manner lessen its effectiveness. Both

the covering 6 and sheet of moisture-proof material 7 are preferably secured to the base member 5 in any desired manner or as shown by the rivets 8 to render the device one complete unit.

- With the structure just previously described herein, it is apparent that the moisture-proof material 7 will effectively prevent any moisture tending to pass through 10 the covering 6 from contacting with the base member, and thus aid in the preservation of this base member, be the same made of metal, felt, cork, or any suitable material.

In Figure 3 of the drawing there is shown 15 a slight modification of the present invention, the structure being identical with that shown in Figures 1, 2 and 4 with the exception that the moisture-proof material, designated 7^a in this instance, covers the entire 20 undersurface of the covering 6.

In this construction, the moisture-proof material 7^a not only prevents moisture from passing through the covering 6 and contacting with the base member 5, but also prevents moisture seeping through the lower 25 portion of the footwear of a user from contacting with the cover 6 or the foot of the user.

Although the present invention has been 30 shown and described herein in connection with an arch support, it is to be clearly understood that the invention may be equally as well used with an insole, heel pad, or any device of similar character.

35 From the foregoing, it will be apparent that I have provided novel foot supporting means in which portions are protected from moisture caused by the foot of a user, and which device is also capable of protecting a 40 foot of a user from moisture entering the lower portion of the said user's footwear, is simple in construction, very durable, and may be economically manufactured.

I am aware that numerous details of construction may be varied through a wide range 45 without departing from the principles of this invention, and I therefore do not purpose limiting the patent granted, otherwise than necessitated by the prior art and the scope 50 and spirit of the appended claims.

I claim as my invention:

1. In an arch support of the character described, a metallic plate, a flexible cover for said plate, a sheet of rubberized material disposed between said cover and said plate for preventing moisture from the foot seeping through said covering and contacting with said plate, and means for securing said sheet to said plate and said cover.

60 2. In an arch support of the character described, an arcuate plate, a flexible covering for said plate, and elastic moisture proof means contacting with the under side of that portion of said covering which overlaps said 65 base plate.

3. In an arch support of the character described, a plate, a rubberized sheeting covering said plate and overlapping the edges thereof, a cover overlying said sheeting, and means for uniting said plate, said sheeting, and said cover.

In testimony whereof I have hereunto subscribed my name at Chicago, Cook County, Illinois.
